WEB SPLICING DEVICE

Hans C. Jordhoy, North Plainfield, and Charles L. Ricards, South Plainfield, N. J., assignors to Wood Newspaper Machinery Corporation, New York, N. Y., a corporation of Virginia

Application October 21, 1933, Serial No. 694,602
Renewed May 5, 1936

18 Claims. (Cl. 242—58)

This invention relates to a device for semi-automatically splicing a new roll of paper to the running web of an expiring roll feeding into a printing press, without materially reducing the printing speed.

The embodiment of the invention shown herein is employed with a conventional magazine reel provided with a speeding-up device for the incoming roll incorporating the principles set forth 10 and claimed in the prior application of Hans C. Jordhoy, Serial No. 652,679 and also a brush arm similar to that shown and claimed in the prior application of Henry A. Wise Wood, Serial No. 650,121.

15 The objects of this invention are to provide improvements in each of the above mentioned devices; to provide for building the driving mechanism for the incoming roll into one of the reel spiders to move integrally with that spider when it is shifted for rolls of different widths 20 or for side register; to provide means for throwing out or disconnecting the roll drive mechanism when the peripheral speed of the incoming roll is the same as the web speed which, of course, is inversely proportional to the diameter of that roll; to provide means whereby when 25 the incoming roll has advanced enough to contact with the traveling web, just prior to the splice, the position of the reel at that time determines the instant of throw off for the drive and regulates the speed of the incoming roll; to provide, in connection with the arm which 30 supports the brush or other means for engaging the web and backing it up when the web and new roll come into contact, a limit switch connected to be operated by the web severing knife to bring the reel forward automatically after the knife has cut the web from the expiring roll and after the said arm is released so that it is 35 allowed to rise, and to provide means whereby the raising of said arm automatically resets the knife, which operation in turn causes the limit switch to stop the reel from rotation.

Other objects and advantages of the invention 40 will appear hereinafter.

45 Reference is to be had to the accompanying drawings, in which

Fig. 1 is an end view of mechanism embodying this invention, showing the parts in the position they assume just prior to splicing with the brush arm down in operative position, the web feeding off the expiring butt, and the new roll just ready to contact with the web;

Fig. 2 is a fragmentary view of parts at the 50 top and right hand of Fig. 1;

Fig. 3 is a sectional view thereof taken on the line 3—3 of Fig. 1;

Fig. 4 is a rear view of the brush arm complete;

Fig. 5 is an end view, opposite that shown in 5 Fig. 1, of the brush arm showing the web and the new roll and illustrating details of the web severing knife;

Fig. 6 is an end view of the brush arm showing details of the latch for holding it in its 10 lowered or operative position and showing the limit switch for preventing reversal of the magazine reel when the arm is in the same position;

Fig. 7 is a sectional view showing details of 15 the limit switch operating mechanism mounted on the brush arm;

Fig. 8 is an end view of the parts for controlling the operation of the roll separated from the rest of the mechanism;

Fig. 9 is a sectional view of one of the clutches 20 and its operating means at the center thereof;

Figs. 10 and 11 are plans of the same showing 25 two different positions;

Fig. 12 is a sectional view of another one of the clutches and its operating means;

Figs. 13, 14 and 15 are views, partly in section, 30 showing details of the solenoid tripped main driving clutch;

Fig. 16 is a sectional view on the line 16—16 35 of Fig. 3 relating to the same mechanism;

Fig. 17 is a horizontal cross section on the line 17—17 of Fig. 4 of one leg of the brush arm with the operating handle knife release in plan, and

Fig. 18 is a wiring diagram.

It will be seen by reference especially to Fig. 1 35 that the invention is illustrated as applied to a conventional three arm reel having a shaft 1 supported by pedestals 2. Mounted on the shaft 1, slidably feathered thereto so as to be laterally movable for different width rolls and for 40 measuring and correcting the margin of the printed product, are two three armed spiders 3. These spiders support the paper rolls in the usual manner. The spider at one end differs from that at the other in that it incorporates 45 the mechanism for driving the incoming roll. The shaft 1 and spiders slidably keyed to it are rotated back and forth by the usual reel motor 4, driven through its worm 5 and worm wheel 6 mounted on the shaft 1, to place the fresh roll 50 R in the proper position for splicing. This motor is controlled through electrical connections illustrated in the wiring diagram, Fig. 18.

The incoming roll R is prepared by cutting the leading end of the paper in a W as partially 55

shown in Fig. 3, the two points being held down by the Wood "autopaster" tab 99 which is a weakened gummed tab of sufficient strength to hold the points down against windage and centrifugal force and weak enough to be torn apart when the glue on the leading end of the incoming roll contacts the running web. The glue is applied to the leading end of the incoming roll in a ribbon about $1\frac{1}{2}$ " wide in the conventional manner.

As shown in Figs. 4, 5, and 6, an arm or frame 7 is employed pivotally supported by a shaft 8 mounted in bearings 9 bolted to the press structure. This arm in general is similar to that shown in the above mentioned case 650,121. While it is called a brush arm, it will be understood that it is a movable frame for supporting any means for pressing the web against the incoming roll or backing up the web when engaged by the incoming roll just at the time of splicing. As in the above mentioned case, this brush arm 7 carries a line of brushes 10 for pressing the running web *w* against the incoming roll *R*. It also carries a corresponding line of knives 13 for severing the web from the expiring butt 14 and for controlling other functions, as will be described later. The arm 7 is oscillated by an operating handle 66 from its operative position which, in the form shown, is practically vertical to its inoperative position at an angle of approximately 45° .

In Fig. 1 a spring roller 15 is shown over which the running web travels. This is mounted on the printing press 12, preferably, and is employed to relieve sudden excessive strains on the web.

A stationary strap web tension device is shown consisting, in this case, of four straps 16 anchored to the floor or at the bottom of the machine at their lower ends. Above they are secured to the ends of four lever arms 17. These arms are pivoted at their centers, each connected with one of the straps 16 and carry adjustable weights 18 on their other ends. These weights act independently of each other to maintain the tension on the straps. When the reel is run forward the running roll is brought further into contact with these straps 16 thereby creating tension on the web. The reason for employing a plurality of brushes and knives is to provide spaces between them for these straps.

One of the spiders 3 is provided with a hub 11 on which is rotatably mounted a large gear 19 which meshes with smaller pinions 20, one on each of the three or other number of roll spindle shafts 21. Each pinion 20 turns freely on its spindle shaft 21 except when engaged with it by a clutch part 22 which is splined to the shaft. This clutch part 22 is operated by trunnions 220 in a yoke on the lower end of a yoke lever 23. This yoke lever is supported on a shaft 24 attached to the spider 3. On the lower extremity of the yoke lever 23 is a spring 25 tending to keep the clutch engaged. The clutch part is normally held in the disengaged position, as shown in Fig. 10, by a hand lever 26 pivotally mounted at its center on a stud on the spider 3. Obviously this lever can be operated manually and is released just prior to splicing. A notch on the end of the lever engages a suitable stud on the upper end of the yoke lever 23. The lever 26 is held by a spring 27 in a position to keep its notch engaged with this stud under normal conditions.

Fig. 11 shows this lever 26 and yoke lever 23

disengaged by the manual operation of the lever and at this time the clutch part 22 comes into operative engagement with the teeth on the pinion 20 to transmit rotation from the gear 19 to that spindle shaft 21.

Referring again to Fig. 3, a member 28 is rotatably mounted on the hub 11 of the spider and bolted to the large gear 19, so as to turn it. This member 28 carries the projection 98 and an arm provided with a cam slot 29 eccentrically arranged. This is employed in the driving of the incoming roll.

Movably mounted in the cam slot 29 is a roller 30 on a stud 31 carried in a gear segment 32. This gear segment is mounted in bearings in a 15 non-rotatable supporting housing 33 outside the other elements described and located on the hub of the spider so as to move laterally with the spider. The upper end of this housing 33 is provided with flanges 340 adapted to run on a guide rail 34 which runs across the press frame 12 parallel with the shaft 4 and acts to allow the spider with its housing 33 to be moved as a unit laterally but prevents the housing 33 from rotating about its center. The gear segment 32 25 meshes with a pinion 35 keyed to a shaft 36 which is mounted in bearings in the housing 33.

Turning freely on the shaft 36 is a gear 37 which meshes with an idler 38 which in turn meshes with a pinion 39 splined to a shaft 40 30 extending across the press 12 parallel with the spider shaft 4. The shaft 40 is driven continuously by the press through a worm 42 connected with the press and worm wheel 41.

Movably splined to the shaft 36 is a clutch 43 35 which may be engaged with complementary clutch teeth on the loose gear 37. It will be remembered that this gear rotates continuously independently of the shaft 36. This clutch 43 is operated by trunnions on a yoke lever 44 supported on shafts and bearings bolted to the housing 33. A tension spring 45 attached to the lower end of the yoke lever tends to keep the clutch 43 engaged with the clutch teeth on the gear 37. This clutch member 43 is adapted 45 to be engaged by a solenoid 51 which operates a dog 46.

Keyed to the shaft 36 is a cam 47, the high point of which engages a roller 48 carried on a transverse arm on the yoke lever 44 to positively throw the clutch 43 out. This high point on the cam is so located as to throw out the clutch just before the completion of one revolution of the shaft 36. After being thrown out it is held out by the dog 46 which has a notched end for that purpose, as shown in Fig. 13.

Figs. 13, 14 and 15 show the connection of the solenoid 51 with the dog 46. The dog is pivotally mounted at its center on a stud 49 located in bearings on the housing 33. One end, as stated, 60 has a notch to engage the yoke lever 44 and the other end is drilled to allow a rod 50 to pass freely through it. The upper end of this rod is attached to the plunger of the solenoid and on the lower end is an adjustable stop nut 52. A 65 weight 53 is slidably mounted on the rod above the stop nut and placed between it and the dog 46. The stop nut 52 is so adjusted that normally the weight 53 just clears the dog 46 when the solenoid is energized and its plunger is drawn up. 70 When this occurs a sudden thrust throws the weight 53 against the end of the dog, releasing its notch on the other end from the yoke lever 44 and allowing the spring 45 to move the yoke lever 44 inwardly to connect the clutch. This 75

arrangement connects the shaft 36 with the gear 37 so that it will rotate with it and insures that the dog 46 will not be held up by the solenoid 51 even though it remains energized. The dog, therefore, is in a position, as soon as the weight 53 drops by gravity against the stop nut 52, to hold the clutch 43 out as soon as it has been opened again by the cam 47. In this case the yoke lever 44 moves over to the position shown in Fig. 13 and the preponderant weight of the other end of the dog 46 swings it up into locking position.

The arm 7 for supporting the brushes or other means for making the paster is in the form of a frame substantially the width of the web. The brushes five in number in the present case, extend the full width of the web except for the four spaces which allow them to drop between the tension straps 16. Also on the brush arm 20 in its lower extremity are five knives 13 arranged in a similar way, all secured to a shaft 54 which is mounted in bearings 55 of the brush arm. On the shaft 54 are two torsion springs 56 for rotating the knife out at right angles into operative position. One end of one spring 56 fits in a hole in a collar 56a secured to the shaft 54. The other end fits in a hole in the knife shaft bearing 55. When the brush arm is lifted into inoperative position the knife is reset or rotated into a parallel position with the brush arm against the torsion of the spring 56 by a crank 57 secured to the knife shaft 54. This crank is operated by a rod 58 pivoted to the press structure. The rod 58 loosely fits into a poppet 59 on the 30 crank 57 and stop nuts 60 on the rod are adjusted so that the knife is reset when the arm 7 is elevated.

When the arm is lowered the knife is held in this reset position by a notched segment 61 secured to the shaft 54, as shown in Fig. 5. In lowering the brush arm the resetting rod travels freely through the poppet 59. The notch in the segment 61 engages a rod 62 which is spring-pressed downwardly by a spring 63 with a stop collar 64 secured to the rod. This rod 62 is raised manually by a lever 65 pivotally connected with it to release the knife when desired. The shaft 8 has keyed to it an operating handle 66 for turning it and it is on this lever that the lever 65 is pivoted.

Since the brush arm 7 oscillates slightly relative to its operating handle 66 when the incoming roll strikes the brushes, it is necessary to provide a loss motion connection somewhere between the knife release lever 65 and the knife release rod 62. This rod, it will be remembered, is mounted on the brush arm while the release lever 65 is mounted on the operating handle 66. Fig. 17 shows the upper end of the rod 62 as slidably mounted on a pin or stud 65a carried in the forked end of the lever 65 and slidably laterally thereon. Therefore, when the brush arm is moved out by the pressure of the incoming roll against the brushes, this rod 62 is free to move forward and back on this stud 65a and permit limited amount of motion of the brush arm relative to the knife release member 65.

As stated, the brush arm 7 is pivotally mounted on the shaft 8 and keyed to that shaft, besides the brush arm operating handle 66, are two levers 67 at the opposite ends of the brush arm. To each of these levers 67 is pivotally connected a rod 68 extending substantially at right angles to the length of the lever. This rod passes loosely through a poppet 69 pivotally

secured to the brush arm 7. On the rod 68 is a spring 70, adjusting nuts 71 and a stop collar 72. The spring 70 presses against the adjusting nut 71 and the poppet 69, holding the poppet against the stop collar. This yieldingly 5 presses the brush arm 7 against the two levers 67 so that, except for the yielding pressure, the brush arm 7 turns with the shaft 8.

On the extreme lower ends of the lever arms 67 are projections 67a for striking the rollers 73a 10 on two limit switches 73 mounted on the brush arm.

As will be described later, the incoming roll R strikes the running web w and forces it against the brushes 10 on the brush arm when the 15 paster is about to be made. This causes the brush arm to spring back the compressing spring 70, thus allowing the projections 67a to operate limit switches 73. As these limit switches are so connected that the motor circuit is broken 20 the motor and reel are stopped. The adjusting nuts 71 are turned to adjust the springs 70 to such an extent that the limit switches will be operated when the correct pressure is obtained between the brushes 10 and the incoming roll R 25 with the web between them.

For the purpose of counterweighting the brush arm it is provided with a segment 80 meshing with a pinion 79 on a shaft 78 mounted in bearings carried on the press frame 12. This 30 shaft carries an arm 76 having a series of perforations into one of which a stud 77 is placed. This stud is adapted to receive a loop on a strap 75 which carries a counterweight 74. This counterweight is adjustable by removing 35 one or more of its separate weights. The segment and pinion are so proportioned and the stud 77 so placed in one of its perforations that the weight 74 will hold the brush arm down when it is placed in its lowermost position and 40 will also hold this arm up when it is raised, because the crank arm 76 will then pass over its dead center, as indicated in dotted lines in Fig. 1.

The mechanism on the brush arm operating 45 handle 66 on the arm is arranged on the arm so that the arm can be unlatched only when pressure is taken off the latch by manual downward pressure on the handle 66. For this purpose hand gripped toggle 81 is mounted on the 50 lower extremity of the handle 66 and held open by the spring 82. A rod 83 on the handle 66 is arranged for holding the brush arm 7 in its lowered operative position. This rod 83 is arranged in substantially vertical position and 55 drops by gravity against a shoulder on the hand gripped toggle 81. When the brush arm is down and the toggle 81 released the rod 83 enters the notch in an adjustable sector 84 carried adjustably in a housing 85 carried by the press frame 12. In order to adjust the length of the rod 83 it is shown as made in two pieces threaded into each other and locked by the lock nut 86.

A limit switch 87 is adapted to be operated by a pin 88 actuated by a cam 89 mounted on 65 the knife shaft 54. This operation is performed so that a circuit is closed when the knife is released and opened when the knife is reset. This limit switch is wired in parallel with the forward reel push button 93 to automatically run the 70 reel forward and bring the new roll against the tension straps, with the web between, after the paster has been made.

Also there is a limit switch 90 in series with a reverse button 94 mounted in the housing 85. 75

A cam 91 fixed on the shaft 8 is set to operate the limit switch 90 so that a circuit is opened when the brush arm 7 is located in the downward position and closed, as far as this switch is concerned, when the arm is up. The reason for wiring this switch in series with the reverse push button 94 is to prevent the possibility of breaking the arm by reversing the reel when the arm is down.

10 The wiring diagram has been described in part. It shows electrical connections for the paster and a conventional reel motor 4 and reel controller. Power is supplied through the switch 95. The closing of either or both of the 15 brush limit switches 73 causes the contactor 96 to close. This in turn opens the circuit to the forward push button 93 and the limit switch 87 to prevent the reel motor 4 from being run further forward. In closing, the contactor 96 also 20 closes a circuit to the clutch solenoid 51 to energize it. The knife limit switch 87 is wired in parallel with the forward reel button 93 and is mechanically operated by the web severing knife 13 to close the circuit when the knife is tripped 25 and open it when the knife is reset. This causes the reel to run forward whenever the knife is tripped and the contactor 96 is opened. The reverse limit switch 90 is wired in series as stated with the reel reverse button 94 so that 30 both of them have to be closed in order to reverse the reel. The limit switch 90 is operated by the brush arm 7 so that it is open when the arm is down and closed when the arm is up. This interlocks the reel so that it cannot be reversed when the arm is down, thereby preventing 35 damage to the arm.

Operation

When the running roll 14 becomes small and 40 just prior to its expiration, the brush arm is lowered manually by its operating handle 66 and is automatically locked down by the rod 83 being forced up by the spring 82 into the notch of the sector 84. The incoming paper roll 45 is rotated backward until the heel of the paste approaches closely to the brush, as shown in Fig. 5. The spindle clutch 22 is then manually engaged by the releasing member 26 allowing the spring 25 to throw the clutch 22 into engagement with the pinion 20.

When the operator decides that the moment for making the paster has arrived, he presses the reel forward button 93 and the reel rotates in a forward direction until the incoming roll R 55 contacts with the running web w and presses it against the brushes 10, which are in stationary position at this time. As the brush arm 7 is yieldingly mounted through the springs 70 it moves back compressing these springs and causing 60 the arms 67 to throw the limit switches 73 into closed position.

As will be seen by reference to the wiring diagram the closing of these switches 73 causes the contactor 96 to be energized closing the circuit at 91 and opens it at 100. This stops the reel from further advance and energizes the clutch solenoid 51, thus throwing the weight 53 up to release the dog 46. This allows the spring 45 to cause the clutch 43 to engage with the gear 37 and transmits power from the shaft 49 to the shaft 36 and to the roll spindle 21. The pinion 35 will make one revolution only and then its cam 47 will throw out the clutch. The rotation of the gear 32 through a partial revolution causes the roller 30 to ride in the slotted

cam 29 and to turn. With it the gear 19 turns and the pinion 20. As the slotted cam 29 sweeps around, the projection 98 attached to the member 28 strikes the upper end of the yoke member 23 forcing the clutch 22 open against the resistance of the spring 25. When the clutch 22 is once opened it is held open by the lever 26, latched into place, as shown in Fig. 10. The disengagement of the clutch 22 takes place just prior to the disengagement of the clutch 43.

10 The position of the spider 3 when the roll R strikes the brush and stops the reel is determined by the diameter of the roll R. The nearer the spindle, on which the incoming roll R is mounted, is located to the brush arm, the 15 longer the travel of the slotted cam 29, before the projection 98 will contact with the yoke lever 23 and therefore the greater the speed of the incoming roll. The slotted cam 29 is so proportioned as to give a uniform acceleration 20 to the roll R and the projection 98 is so located that when it contacts the clutch yoke lever 23 the speed of the roll R will be approximately equal to the speed of the web. In this manner 25 the position of the reel is used to determine the speed ratio of the incoming roll.

When the pasted leading edge of the roll R contacts with the running web w the "auto-paster" tabs 99 will be torn apart and the web 30 of the incoming roll attached to the running web so that both webs will be fed into the press. When the operator sees the second web attached he presses the knife release handle 65 which drops the knife and severs the web w from the butt 14 and closes the circuit in the limit switch 35 87. The closing of this switch will perform no present function, as will be seen by the wiring diagram, until the limit switches 73 open. Then the contactor 96 will open completing the forward reel circuit and deenergizing the clutch 40 magnet 51. The brush arm is released by grasping the toggle 81 on handle 66 and pressing it forward, thus allowing the rod 83 to drop by gravity out of the notch in the sector 84.

It will be apparent therefore that the reel will 45 then go forward bringing the roll R into the tension straps 16. Tension will be held on the web from the roll R by the counterweights 74 which, at this time, tend to hold the brush arm in its lowered operative position. As the reel runs forward it causes the brush arm 7 to rise. Raising the arm resets the knife 13 which in turn opens the limit switch 87 and causes the reel to stop, the paster having been completed. When the cam 47 releases the main driving clutch member 50 28, which carries the slotted cam 29 and projection 98, this member 28 will be returned to its starting position by a spring 102 attached thereto.

It will be seen therefore that the entire apparatus is back now in its starting position ready 60 for making another paster on the next succeeding roll.

Although we have illustrated and described only one form of the invention we are aware of the fact 65 that modifications can be made therein by any person skilled in the art without departing from the scope of the invention as expressed in the claims. Therefore, we do not wish to be limited in this respect otherwise than as set forth in the 70 claims, but what we claim is:—

1. In a web splicing device, the combination with a printing press frame to which the web is fed, said frame having a stationary guide rail extending transversely, of a shaft parallel with 75

- the guide rail, spiders carried by said shaft and constituting therewith a reel for the web rolls, one of said spiders being movable along the shaft, a shaft on the press frame adjacent to 5 said rail, a housing connected with the first-named shaft for engaging said rail to guide the spider thereby when the spider moves, a gear on said press frame shaft, a shaft carried by the housing, means for driving the last named shaft 10 from said gear, a segment carried by the housing, means for oscillating the segment from the housing shaft, and means operated by the segment for turning the spindle of the fresh web roll to speed it up prior to splicing, the last-named means 15 being carried by the spider.
2. In a web splicing device, the combination with a printing press frame and a reel comprising a rotatable shaft and spiders carried by the shaft, of a shaft carried by the printing press 20 frame, means for rotating the last-named shaft from the press, a housing supported by the shaft of the reel in non-rotatable position, a shaft carried by the housing, means detachably connected with the last-named shaft for rotating it with 25 the printing press shaft, a segment connected with the shaft on the housing to be turned thereby, a series of web roll spindles on the reel, each having a loose gear thereon, means for connecting said loose gear with its spindle and disconnecting it therefrom, and means connected with 30 said segment for turning said loose gear for the purpose of rotating the fresh web roll approximately to web speed from the shaft on the press.
3. In a web splicing device, the combination 35 with a rotary reel for supporting the web rolls and a spindle shaft on the reel for each web roll, of a driving means for turning the spindle shaft for the new web roll comprising a rotary segment having a cam roller mounted to turn in stationary bearings, a gear mounted to turn on 40 the reel, a transmitting member comprising a curved cam for receiving said roller fixed to the gear and having such shape as to bring the surface of the fresh web roll up to substantially web speed, a clutch for disconnecting the gear from 45 the spindle shaft, and means movable with the cam for throwing the clutch out when the fresh web roll rotates at substantially web speed.
4. In a web splicing device for a printing press, 50 the combination with a reel having a plurality of spindle shafts thereon for supporting a plurality of web rolls, of means operated by the press for rotating each of said spindle shafts on its own axis when it is carrying the fresh web 55 roll, a clutch for throwing out the connection of the spindle shaft with said means, said clutch having a lever for throwing it out, and a member rotatable on the axis of the reel but at a different speed for engaging said lever and throwing the 60 clutch out when the spindle rotates fast enough to bring the surface of the fresh web roll up to web speed.
5. In a web splicing device, the combination 65 with a printing press frame and a shaft thereon driven by the press, of a reel having a shaft, a housing mounted in non-rotatable position on the shaft and the press frame, a third shaft on the housing, gearing carried by the housing for transmitting the rotation of the first-named 70 shaft to the third shaft, a clutch for connecting said gearing with the third shaft, means driven by the clutch for rotating on its own axis a fresh web roll carried by said reel, and means for throwing the clutch out at the end of a complete rotation of said third shaft.
6. In a web splicing device, the combination with a printing press frame and a shaft thereon driven by the press, of a reel having a shaft, a housing mounted in non-rotatable position on the shaft and the press frame, a shaft carried by the housing for transmitting the rotation of the first-named shaft, a clutch for connecting the first shaft with the third shaft, means driven by the third shaft for rotating on its own axis a fresh web roll carried by said reel, 10 means for throwing the clutch out at the end of a complete rotation of said third shaft, a pivoted dog for holding the clutch out, a spring tending to close the clutch, a solenoid adapted to operate the dog to release it from the clutch, 15 and means whereby the circuit of the solenoid will be closed by the rotation of the roll-driving means to energize it.
7. In a web splicing device, the combination 20 of a shaft, a gear loose on the shaft, means for transmitting power to the gear, a clutch for clutching the gear to the shaft, means for throwing the clutch out upon the completion of a revolution of the shaft, a spindle shaft for a fresh web roll movable bodily along a course 25 toward splicing position, means for transmitting the rotation of the first-named shaft to the spindle shaft when it is adjacent to splicing position, and means for holding the clutch out.
8. In a web splicing device, the combination 30 of a shaft, a gear loose on the shaft, means for transmitting power to the gear, a clutch for clutching the gear to the shaft, means for throwing the clutch out upon the completion 35 of a revolution of the shaft, a spindle shaft for a fresh web roll, means for transmitting the rotation of the first-named shaft to the spindle shaft when the spindle shaft is substantially in position for the web to be spliced, a pivoted dog for holding the clutch out, a solenoid having 40 a depending rod with a stop on the end of the rod, a weight loosely mounted on the rod above the stop, said dog having a tail extending above said weight, whereby, when the rod is pulled up by the energizing of the solenoid, the upward 45 throw of the weight will engage the tail of the dog, disconnect the dog from the clutch, release the clutch and cause the solenoid to be deenergized.
9. In a web splicing device, the combination 50 with a rotary reel for supporting a fresh web roll, means for rotating the reel, and a movable arm between which and the fresh web roll the web from the running roll passes, of a lever mounted to move relatively to the movable 55 arm, yielding means for connecting the lever and the arm for permitting a relative motion when the web roll on the reel moves against the web and forces the web and the arm back, and electrical means actuated by said movement 60 of the arm relative to the lever for stopping the reel rotating means, whereby the time at which the reel is stopped is determined by the diameter of the fresh web roll.
10. In a web splicing device, the combination 65 with a rotary reel for supporting a fresh web roll, means for rotating the reel, and a movable arm between which and the fresh web roll the web from the running roll passes, of a lever mounted to move relatively to the movable arm, 70 yielding means for connecting the lever and the arm for permitting a relative motion when the web roll on the reel moves against the web and forces the web and the arm back, electrical means actuated by said movement of the arm 75

relative to the lever for stopping the reel rotating means, means for rotating the fresh web roll on its axis, said means comprising a rotary cam and a roll operating on the cam, means 5 for moving the roll to actuate the cam, and means for transmitting the motion of the cam to the fresh web roll to rotate it.

11. In a web splicing device, the combination of an arm pivoted to swing on a horizontal 10 axis, means on the arm for backing up the web when a fresh web roll moves against it, a counterweight adjustably connected with said arm, and means whereby the counterweight will hold the arm either in operative position to back 15 up the web or in inoperative position.

12. In a web splicing device, the combination of an arm pivoted to swing on a horizontal axis, means on the arm for backing up the web when a fresh web roll moves against it, a counterweight 20 adjustably connected with said arm, a segment fixed to move with the arm, a shaft parallel to said axis and having a pinion thereon, and an arm projecting therefrom, the last-named arm having means by which the counterweight can 25 be connected to it in adjusted positions, said last-named arm being adapted to hold the first arm in either of its two extreme positions, for the purpose described.

13. In a web splicing device, the combination 30 of a swinging arm, means on the arm for backing up the web, a reel carrying a fresh web roll, means for moving the reel to bring the fresh web roll into contact with the web and force it against the backing up means, a contactor movable with the arm, a limit switch connected with the contactor to close it, means whereby, when the contactor closes, a circuit will be opened, and an additional limit switch in the circuit 35 in position to prevent the reel from being run forward thereafter.

14. In a web splicing device, the combination 40 of a swinging arm, means on the arm for backing up the web, a reel carrying a fresh web roll, means for moving the reel to bring the fresh web roll into contact with the web and force it against the backing up means, a contactor movable with the arm, a limit switch connected with the contactor to close it, an additional limit 45

switch, a solenoid adapted to be placed in the circuit by the closing of the last-named limit switch, and means operated by said solenoid for connecting up the spindle shaft of a fresh web roll with a source of power to rotate the roll 5 on its axis up to web speed.

15. In a web splicing device, the combination of a swinging arm, means for backing up the web on said arm, a reel for supporting a fresh web roll, a reverse limit switch operated by the 10 motion of the arm between operative and inoperative position so that when the arm is down in operative position, the limit switch is open, a motor for operating the reel, said limit switch being connected with the circuit of the motor to 15 reverse it when closed, whereby the reel is interlocked when the arm is up in inoperative position so that the reel cannot be reversed when the arm is down in operative position.

16. In a web splicing device, the combination 20 with a rotatable magazine reel for mounting a plurality of web rolls, a fresh web roll and a running web, and power-operated means for accelerating the fresh web roll in less than one revolution so that its periphery will travel at the 25 speed of the running web, of means for regulating the speed of angular rotation of the fresh roll with respect to the roll's diameter.

17. In a web splicing device, the combination 30 of a rotatable magazine reel for mounting a plurality of web rolls, means for rotating the reel, a fresh roll, a running web, and power-operated means for accelerating the fresh web roll in less than one revolution so that its periphery will travel at the speed of the running web, with 35 means controlled by the angular position of the reel for regulating the speed of the fresh roll.

18. In a web splicing device, the combination 40 of a rotatable magazine reel for mounting a plurality of web rolls, means for rotating the reel, a fresh roll, a running web, power-operated means for rotating the fresh roll, and web-pressing means, with means for starting the web roll rotating means when the fresh roll presses the web against the web-pressing means. 45
